UNITED STATES PATENT OFFICE.

SAMUEL G. GOSS, OF GLENCOE, ILLINOIS, ASSIGNOR TO THE GOSS PRINTING PRESS COMPANY, OF CHICAGO, ILLINOIS, A CORPORATION OF ILLINOIS.

CHANGE WEB-ROLL MECHANISM.

1,301,122.

Specification of Letters Patent. Patented Apr. 22, 1919.

Application filed November 13, 1916. Serial No. 131,159.

To all whom it may concern:

Be it known that I, SAMUEL G. Goss, a citizen of the United States, and a resident of Glencoe, in the county of Cook, State of Illinois, have invented certain new and useful Improvements in Change Web-Roll Mechanism, of which the following is a specification, reference being had to the accompanying drawings.

- 10 My invention relates to change web roll mechanisms for printing presses and the like and it has for its principal object the provision of a new and improved form and arrangement of mechanism by which the web 15 from a fresh roll in normal operative position upon its framework may be spliced to the web being fed to the press from another roll in another operative position upon the framework without the necessity for stopping or even slowing down the press. It is 20 one of the objects of my invention to provide new and improved means for setting in rotation a fresh roll of paper preliminary to the splicing operation, such roll-rotating 25 means being preferably located between the two rolls so as to be adapted to be brought into operative engagement with either roll as desired. It is another object of my invention to provide a new and improved form 30 of stripping mechanism which is adapted to be held out of engagement with a fresh roll to permit its free rotation, and then to be brought into operative position relative to such fresh roll so as to strip the leading 35 end of the web from the roll, suitable guides being provided for directing the end of the web into contact with the web being fed to the press from the other roll. It is another 40 object of my invention to provide a form of stripper mechanism comprising a plurality of strippers adapted to be brought into contact with a fresh roll near its uppermost part so as to extend between the body of the roll and the end of the web for releasing 45 the web from the roll and for supporting the web as it unwinds from the roll for directing such web toward the web being fed to the press from the other roll. It is another 50 object of my invention to provide means controlled by the size of the roll as it decreases in the printing operation for maintaining the strippers in the desired position relative to the roll so as to prevent the strippers from interfering with the normal 55 operation of the mechanism. It is another

object of my invention to improve mechanisms of this type in sundry details herein-after pointed out. The preferred means by which I have accomplished my several objects are illustrated in the drawings and are 60 hereinafter specifically described. That which I believe to be new and desire to cover by this application is set forth in the claims.

In the drawings:

Figure 1 is a side view of my improved mechanism, looking toward the ends of the rolls;

Fig. 2 is a view of my mechanism as seen from the right in Fig. 1;

Fig. 3 is a vertical cross-section through my mechanism, looking toward the right in Fig. 2, but illustrating a changed position of some of the parts;

Fig. 4 is an enlarged detail showing the 75 construction of the pressing rollers by which the two webs are pressed together for effecting the suitable splicing of the webs, the figure being a sectional view taken substantially on line 4-4 of Fig. 3;

Fig. 5 is an enlarged detail illustrating the latching mechanism for holding the upper set of strippers out of engagement with the fresh roll in the upper position preparatory to the splicing operation, being substantially a section taken on line 5-5 of Fig. 2;

Fig. 6 illustrates the latching mechanism for the lower set of strippers, being substantially a section taken on line 6-6 of Fig. 2;

Fig. 7 is a side view of a modified form of mechanism; and

Fig. 8 is a diagrammatic view similar to Fig. 7, but showing a changed position of the parts.

Referring to Figs. 1 to 6, in which corresponding parts are indicated by the same reference characters,

15 indicates a frame located in a compartment or room below the room in which a printing press 16 is located. Rolls of paper 17-18 are supported by spindles 19-20, respectively, mounted in suitable bearings upon arms 21-22 extending from the frame- 100 work 15. The web 23 from the lower roll 18 which is shown in use in Fig. 1 extends from such roll into the bite of endless tape belts 24-25, the adjacent portions of which 105 are driven from the press 16 by any suitable 110

mechanism, not shown, in the direction indicated by the arrow in Fig. 1. Above the tape belts 24 there are provided a plurality of similar endless tape belts 26 also driven at the same surface speed as that of the web, being driven in the direction indicated by the arrow adjacent thereto in Fig. 1. The tape belts 24 are supported by a plurality of sheaves or pulleys 27 mounted upon transversely-extending shafts 28-29. The belts 25 are supported by sheaves or pulleys 30 mounted upon transversely-extending shafts 31, 32 and 33, being further controlled by engagement in suitable grooves in a roller 34 (see Fig. 4) revolvably carried by the framework 15. The endless tape belts 26 are supported at their upper ends by sheaves or pulleys 35 mounted upon a transversely-extending shaft 36, being supported at their lower ends by a grooved roller 37 (see Fig. 4) which is in contact with the roller 34, the rollers 34 and 37 being adapted to yield sufficiently to permit the passage of the web 23 between the rollers. Additional sheaves or pulleys 38 carried by a transversely-extending shaft 39 bear upon the belts 26.

When the web is being fed to the press from a roll in either of the two positions occupied by the rolls 17-18, a fresh roll is placed in position in the other position. Before the web is entirely exhausted from the roll in use, the end portion of the fresh roll is prepared substantially as shown in connection with the roll 17 in Fig. 2. In such preparation the end portion of the web is preferably narrowed toward its extreme end as shown in this figure, but that is not essential to the operation of the mechanism and my claims are not to be limited to such a preparation of the web except as hereinafter particularly specified. The end portion of the web is secured to the body of the roll by any suitable means which are adapted to release the end readily upon the application of a slight force thereto as hereinafter described. The means shown in the drawings are in the form of stickers or pasters 40 which are preferably formed of light paper which is adapted to be torn readily across. Paste or gum of any suitable type is applied to the end of the web, as at 41, spaces being left between the gummed portions for contact of the tapes 24, 25 and 26 with the web without coming in contact with such gum. Other spaces are left for engagement with the periphery of the roll by the means by which the roll is set in rotation preparatory to the splicing operation. The extreme end of the web is buckled outward between the pasters 40 so as to permit the entrance of strippers as hereinafter described between the end of the web and the body of the roll. When the web from one roll is substantially exhausted the other roll is to be set into rotation at the same surface speed as that of

the web running to the press. The strippers are held out of engagement with the fresh roll, permitting such roll to be rotated freely until the web is substantially exhausted from the old roll. The strippers are then released and moved toward the fresh roll, being adapted in the course of the next-successive complete rotation of the fresh roll to pass between the end portion of the web and the body of the roll, serving to strip the end from the roll for permitting the unwinding of the web. The gummed end of the web of the fresh roll is then directed by the means hereinafter described into contact with the old web with which it is duly spliced and led through the press. When the gummed end of the new web has been pressed into contact with the old web, the old web is to be torn across by the hand of the operator or by any suitable severing means which may be provided as desired.

The means for rotating the fresh roll, having its end portion gummed and secured releasably in position, comprises in the construction shown a pair of belts 42-43 which are adapted to be swung into contact with a fresh roll in position upon either one of the spindles 19-20. The belts 42-43 are supported at their inner ends by sheaves 44 fixed upon a shaft 45 extending across the framework 15. The outer ends of the belts 42-43 are supported by sheaves 46 which are revolvably mounted between arms 47-48 which are carried by sleeves 49 revolvably mounted upon the shaft 45. The end sleeves 49 are adapted to be rocked by means of arms 50 extending outwardly therefrom, the outer ends of which are connected by means of links 51 and arms 52 with a transversely-extending shaft 53 which in turn is adapted to be rocked by means of a hand-lever 54. As is best shown in Fig. 3, the arms 47-48 for each belt 42-43 are connected by means of cross-bars 55-56 for bracing such arms relative to each other. In the construction shown, the intermediate sleeve 49 is not connected directly with the shaft 53, and it is believed that no such direct connection is necessary, but it will be understood that I do not restrict my invention in this respect. The hand lever 54 is adapted to be secured in either of three positions upon the rack 57, for holding the belts 42-43 in an intermediate neutral position so as to be out of contact with both rolls, or in an operative position in contact with either an upper or a lower roll as desired.

The shaft 45 is adapted to be rotated in either direction as desired by means of a bevel gear 58 fixed upon one end of the shaft, meshing with bevel gears 59-60 loosely mounted upon a vertically-extending shaft 61 driven from any suitable portion of the press 16. A clutch mechanism 62 of any suitable type is mounted upon the shaft 61

between the bevel gears 59—60 for connecting either gear with the shaft 61 as desired, such clutch mechanism being adapted to be operated by means of a hand-lever 63. As 5 will be readily understood, when the belts 42—43 are raised into contact with the fresh roll in the upper position, the gear 58 may be connected through the proper gear 59—60 for driving the upper roll in clockwise direction in Fig. 1. On the other hand, when it is desired to rotate a fresh roll in the lower position through the medium of the belts 42—43 lowered into contact therewith, the gear 58 will be rotated in the opposite direction for driving such fresh lower roll in 10 counterclockwise direction in said Fig. 1. The shaft 61 is driven constantly from the press at such a speed as to drive the belts 42—43 at the same surface speed as that of 15 the web running through the press, serving thus to give the fresh roll in either position a similar surface speed.

Two sets of strippers are provided, one for a fresh roll in the lower position and the 20 other for a fresh roll in the upper position. The strippers of the lower set are indicated by the numeral 64, being fixedly mounted upon a transversely-extending shaft 65 about which they are adapted to swing. 25 The shaft 65 is provided with a notched collar 66 upon one end with which a latch 67 is adapted to engage for holding the shaft 65 against rotation in clockwise direction in Figs. 1, 3 and 6, the arrangement being such 30 that the latch 67 when in use serves to hold the strippers 64 in their uppermost position well out of contact with a fresh roll in the lower position. The strippers of the upper set are indicated by the numeral 68, being 35 fixedly mounted upon a shaft 69 about which they are adapted to swing. The shaft 69 is provided with a notched collar 70 with which a latch 71 is adapted to engage for holding the shaft against rotation in counter-clockwise direction in Figs. 1, 3 and 5, the arrangement being such that the latch 71 40 is adapted to hold the strippers 68 in their lowermost position well out of contact with a fresh roll in the upper position. A spring 50 72, connected by means of an arm 73 with the shaft 69 tends to force the strippers 68 upward.

With a fresh upper roll 17 in position having its end properly gummed and 55 cured by pasters, when the web from the lower roll 18 becomes substantially exhausted the clutch lever 63 is operated for setting the belts 42—43 in operation so as to move their upper portions toward the left in Fig. 60 1. The lever 54 is then moved to the limit of its motion toward the left in Fig. 1, serving to swing the belts 42—43 upward into contact with the roll 17, serving to set such roll into rotation at the same surface speed 65 as that of the web 23. At the desired mo-

ment the latch 71 is turned out of operative engagement with the notched collar 70, permitting the spring 72 to move the strippers 68 upward into contact with the body of the rotating roll 17. When the buckled out end 70 of the web of the fresh roll comes in the rotation of the roll to the position of the innermost stripper 68, the stripper passes between the web and the body of the roll, tearing the pasters 40 in two for releasing 75 the end of the web for unwinding. The new web thus released from the roll 17 is carried forward by its momentum along guides 74 which are supported in position by a cross-bar 75. The end of the web is directed by 80 such guides into contact with the web 23, being pressed forcibly against the web 23 between the rollers 34—37 for effecting a proper splicing of the new web to the old 85 web 23.

After the new web from the roll 17 has been spliced to the old web 23 and the old web has been torn across by any suitable means, the spindle 20 is removed and a fresh roll is inserted in the lower position after 90 the strippers 64 have been raised to their uppermost position where they are held by the latch 67. The end of the web of the new roll, being the roll 76 shown in Fig. 3, is prepared substantially as shown in connection with the roll 17 in Fig. 2. At the proper time the roll 76 is set in rotation and the strippers 64 are released to strip the end of the web from the fresh roll 76. The released end of the fresh roll 76 is guided by 100 the strippers 64 themselves into the bite of the belts 24—25 by which it is carried upward into contact with the web 77 being fed to the press from the roll 17, the rollers 34—37 again serving to complete the splicing 105 operation by pressing the gummed end of the fresh web forcibly against the web running from the roll 17.

The means provided in the construction shown for controlling the position of the 110 strippers 64—68 comprises a train of arms and links provided with rollers adapted to bear upon the rolls. The shaft 69 is provided with an arm 78 fixedly mounted thereon which is connected by means of a link 115 79 with an arm 80 fixedly mounted upon a sleeve 81 from which depends an arm 82 which carries at its lower end a roller 83. As will be readily understood, as the roller 83 is permitted to move to the right in Fig. 1 under the influence of the spring 72, the strippers 68 will be gradually raised so as to be kept out of objectionable contact with the upper roll and out of contact with the web coming from such roll. The means for 120 controlling the strippers 64 comprises an arm 84 mounted upon the shaft 65 connected by means of a link 85 with an arm 86 fixedly mounted upon a sleeve 87 upon which is fixedly mounted an arm 88 which carries at 125 130

its end a roller 89 adapted to bear upon the lowermost roll. A spring 90 connects the arm 86 with a bracket 91 extending from the frame 15, serving to hold the arm 86 5 yieldingly in its uppermost position.

In Figs. 7 and 8 which show a modified form of construction, parts which correspond substantially to the construction above described are provided with the same reference characters but with the addition of an exponent "a". In this construction the strippers 64^a direct the web from the lower roll directly into the bite of endless tape belts 92-93 which are supported by means of 10 sheaves or pulleys 94 mounted upon transversely-extending shafts 95 in suitable position. The guides 74^a direct the end of the webs stripped from the upper roll likewise to the bite of the same two sets of tape belts 92-93. The bevel gear 58^a in the construction here shown is not fixed directly upon the shaft 45^a, but is suitably connected with the roll-rotating belts through the medium of suitable interposed gearing. The means for 15 swinging the roll-rotating belts comprises a handle 96 mounted directly upon the shaft 45^a in lieu of the construction shown in Fig. 1 involving the lever 54 and the link and arm connection. It is believed the operation 20 of the construction shown in Figs. 7 and 8 will be fully understood without giving a detailed description of the same, inasmuch as it is in effect the same as that already 25 described.

35 So far as I am aware, I am the first in the art to provide for supporting a web roll adjacent to a running web and for rotating said roll independently of its supporting means substantially at the same surface 40 speed as that of the running web, means being provided for leading the end of the web from the roll in either position into contact with the running web for securing said two webs together, and my claims are 45 to be construed accordingly. It will be understood that I do not wish to be restricted to the details of the construction illustrated, except as hereinafter specifically claimed, inasmuch as the construction can 50 manifestly be changed in many ways without departing from the spirit of my invention.

What I claim as my invention and desire to secure by Letters Patent, is—

55 1. Apparatus for feeding a web to a printing press, comprising an endless driving band, spaced pulleys upon which said band is mounted, one of which is held in fixed bearings and the other in bearings radially 60 movable with respect to the fixed bearings, and means for bringing the movable bearings into one position whereby the endless band contacts with one web roll or into a position in an opposite direction whereby

the endless band contacts with another web 65 roll.

2. Apparatus for feeding a web to a printing press, comprising an endless driving band, spaced pulleys upon which said band is mounted, one of which is held in fixed 70 bearings and the other in bearings radially movable with respect to the fixed bearings, means for bringing the movable bearings into one position whereby the endless band contacts with one web roll or into a position in an opposite direction whereby the 75 endless band contacts with another web roll, and means for reversing the direction of movement of the said driving band.

3. The combination of means for supporting a plurality of rolls in operative position for alternative use, means for rotating a fresh roll in either position while the web is being drawn from another roll, and means associated with said rolls for leading the 80 end portion of the web from the fresh roll into contact with the web from the other roll when the latter is running at its normal speed.

4. The combination of a frame adapted to receive a roll in either of two positions independently of a roll supported in the other of said two positions, means for rotating a fresh roll in either position while the web is 90 being drawn from the other roll in the other 95 position, means securing the end portion of the web of the fresh roll in position upon the roll adapted normally to prevent unwinding of the web, stripper means adapted when moved toward a fresh roll in one position to pass between the body of the roll and the end of the web for releasing the end of the web, other stripper means adapted when moved toward a fresh roll in the other position to pass between the body of the 100 roll and the end of the web for releasing the end of said web; and means for guiding the end of the web from the fresh roll in either 105 position into contact with the web being drawn from the roll in the other position. 110

5. The combination of a frame adapted to receive a roll in either of two positions independently of a roll supported in the other of said two positions, means for rotating a fresh roll in one of said positions while the 115 web is being drawn from the other roll in the other position, means securing the end portion of the web of the fresh roll in position adapted normally to prevent unwinding of the web, and stripper means adapted 120 to be moved toward said fresh roll substantially into contact with its upper portion adapted to engage the under face of the end portion of the web and to support the web as it unwinds from the roll after having its 125 end portion released by the stripper means.

6. The combination of means for revolvably supporting a plurality of rolls in opera-

- tive position for alternative use, means for bringing the fresh roll to a surface speed substantially equal to the speed of the web in use, and stripper means for each roll, 5 each of said stripper means being pivotally mounted on a fixed axis and adapted when swung toward its roll to pass between the roll proper and the end portion of the web for releasing the web for unwinding.
- 10 7. The combination of means for revolvably supporting a plurality of rolls in operative position for alternative use, means acting independently of the supporting means for rotating said rolls, and stripper mechanism for each roll, each stripper mechanism being adapted to be swung at any time as desired toward its roll for stripping the end of the web from the roll for unwinding.
- 15 8. The combination of a frame, means for revolvably supporting a roll of paper upon said frame, means for rotating said roll, means securing the end of the web of said roll lightly in position upon the roll adapted normally to prevent unwinding of the 20 web, spring-pressed stripper means adapted normally to move toward the roll and adapted when moved into close proximity to the roll to extend between the roll and the end of the web for releasing the web for unwinding, and latch mechanism for holding the stripper means away from the roll.
- 25 9. The combination of a frame, means for revolvably supporting a roll of paper upon said frame, means for rotating said roll, means securing the end of the web of said roll lightly in position upon the roll adapted normally to prevent unwinding of the web, stripper means tending normally to move toward said roll for stripping the end 30 of the web from the roll for unwinding, and latch mechanism for holding said stripper means out of operative position relative to said roll adapted to be released manually at any time for permitting the stripper mechanism to operate.
- 35 10. The combination of a frame, means for revolvably supporting a plurality of rolls each in operative position, means for rotating said rolls, and stripper means pivotally mounted adjacent to each roll and adapted to swing downward by its own weight into contact with the upper portion of the appropriate roll for stripping the end of the web from the roll.
- 40 45 11. The combination of a frame, means for revolvably supporting a roll of paper in said frame, means for rotating said roll, means securing the end of the web of said roll lightly in position upon the roll adapted normally to prevent unwinding of the web, stripper means pivotally mounted adjacent to said roll adapted to swing downward by its own weight into contact with the upper portion of the roll for stripping
- the end of the web from the roll, and latch mechanism for holding said stripper means away from the roll.
- 50 12. The combination of a frame, means for revolvably supporting a roll of paper in said frame, means for rotating said roll, means securing the end of the web of said roll lightly in position upon the roll adapted normally to prevent unwinding of the web, stripper means movably mounted adjacent to said roll and adapted to be moved into close proximity to the roll, and means controlled by the size of the roll for regulating the position of the stripper means relative to the roll.
- 55 13. The combination of a frame, means for revolvably supporting a roll of paper in said frame, means for rotating said roll, means securing the end of the web of said roll lightly in position upon the roll adapted normally to prevent unwinding of the web, stripper means movably mounted adjacent to said roll and adapted to be moved into close proximity to the roll, yielding means tending to move said stripper means toward said roll, and means controlled by the size of the roll for regulating the movement of the stripper means toward the roll.
- 60 14. The combination of a frame, means for revolvably supporting a roll of paper in said frame, means for rotating said roll, means securing the end of the web of said roll lightly in position upon the roll adapted normally to prevent unwinding of the web, stripper means movably mounted adjacent to said roll and adapted to be moved into close proximity to the roll, and an arm connected with said stripper means and adapted to engage said roll upon its periphery for regulating the position of the stripper means relative to the roll.
- 65 15. The combination of a frame, means for revolvably supporting a roll of paper in said frame, means for rotating said roll, means securing the end of the web of said roll lightly in position upon the roll adapted normally to prevent unwinding of the web, stripper means movably mounted adjacent to said roll and adapted to be moved into close proximity to the roll, an arm connected with said stripper means for regulating the position of the stripper means relative to the roll, and a roller revolvably carried by said arm adapted to engage the periphery of said roll.
- 70 75 16. The combination of a frame, means for revolvably supporting a roll of paper in said frame, means for rotating said roll, means securing the end of the web of said roll lightly in position upon the roll adapted normally to prevent unwinding of the web, stripper means movably mounted adjacent to said roll and adapted to be moved into close proximity to the roll, an arm pivotally

mounted adjacent to said roll, connections between said arm and said stripper means for causing said arm and said stripper means to move in unison toward and from 5 said roll, and a roller revolvably carried by said arm adapted to engage the periphery of said roll.

17. The combination of a frame adapted to receive a roll in either of two positions 10 independently of a roll supported in the other of said two positions, means for rotating a fresh roll in either position while the web is being drawn from the other roll in the other position, a plurality of co-acting 15 endless belts adjacent to said rolls, and means for guiding the end portion of the web of the fresh roll in either position into the bite of said endless belts.

18. The combination of a frame, means 20 for revolvably supporting a roll of paper in said frame, means for rotating said roll, means securing the end of the web of said roll lightly in position upon the roll adapted normally to prevent unwinding of the 25 web, stripper means movably mounted adjacent to said roll and adapted to be moved into close proximity to the upper portion of said roll for stripping the end of the web from the roll, and a plurality of co-acting 30 endless belts adjacent to said roll, said strippers being adapted to guide the end of the web into the bite of said belts.

19. A web roll changing mechanism comprising means for revolvably supporting in 35 operative position for alternative use a fresh roll and a roll in use, means for driving the fresh roll at a surface speed substantially equal to that of the web in use, and means for conducting the leading end of the fresh 40 roll to and joining it with the end of the web in use.

20. The combination of a frame, means on 45 said frame for revolvably supporting a roll adjacent to a running web, an endless belt adapted to be moved into and out of contact with the periphery of said roll adapted for rotating the roll, means for driving said belt, and means for guiding the end portion of the web from said roll into contact with 50 the running web for securing said two webs together.

21. The combination of a frame, a web roll revolvably mounted on said frame adjacent to a running web, means lightly securing 55 the end portion of the web of said roll in position upon said roll for preventing unwinding of the web, a coating of adhesive material extending partially across the outer face of the end portion of the web of said 60 roll, an endless belt mounted on said frame and adapted to be swung into and out of contact with the periphery of said roll at a point at which the end of the web is free of adhesive matter, means for driving said 65 belt for rotating said roll at substantially

the same surface speed as that of the running web, and means for stripping the end of the web from said roll and directing it into contact with the running web for securing said two webs together. 70

22. The combination of a frame, means on said frame for supporting two rolls adjacent to each other on said frame, means adapted to be moved into contact with the periphery of either of said two rolls as desired for rotating such roll, and means for splicing the end of the web from one roll to the web being drawn from the other roll. 75

23. The combination of a frame, means on said frame for supporting two rolls adjacent to each other on said frame, an endless belt adapted to be swung into contact with the periphery of either of said two rolls as desired for rotating such roll, and means for splicing the end of the web from one roll 80 to the web being drawn from the other roll. 85

24. The combination of a frame, means on said frame for supporting two rolls adjacent to each other on said frame, an endless belt adapted to be swung into contact with 90 the periphery of either of said two rolls, means for driving said endless belt in either direction for rotating either of said rolls in the desired direction, and means for splicing the end of the web from one roll to the 95 web being drawn from the other roll.

25. The combination of a frame, means on said frame for supporting two rolls adjacent to each other on said frame, an endless belt adapted to be swung into contact 100 with the periphery of either of said two rolls as desired for rotating such roll, means for swinging said belt in either direction and for locking it in either operative position or in an intermediate inoperative position, 105 and means for splicing the end of the web from one roll to the web being drawn from the other roll.

26. The combination of a frame, means on said frame for supporting two rolls adjacent to each other on said frame, an endless belt adapted to be swung into contact with the periphery of either of said two rolls, a clutch for driving said endless belt in either direction for rotating either of 115 said rolls in the desired direction, and means for splicing the end of the web from one roll to the web being drawn from the other roll. 110

27. The combination of means for supporting a plurality of rolls each in operative 120 position, means for rotating a fresh roll in either position while the web is being drawn from another roll, and separate means associated with each roll for guiding the end portion of the web of the fresh roll into 125 contact with the web from the other roll, while the latter is running at its normal speed.

28. A web roll changing mechanism comprising means for revolvably supporting in 130

operative position for alternative use a fresh roll and a roll in use, means for driving the fresh roll at a surface speed substantially equal to that of the web in use, and means 5 for conducting the leading end of the fresh roll with paste applied to the outer surface thereof to and joining it with the web in use.

29. A web roll changing mechanism comprising means for revolubly supporting in operative position for alternative use a fresh roll and a roll in use, means for driving the fresh roll at a surface speed substantially equal to that of the web in use, and devices 15 associated with said rolls for conducting the leading end of the fresh roll to and joining it with the web in use.

30. A web roll changing mechanism comprising means for revolubly supporting in operative position for alternative use a fresh roll and a roll in use, and driving means 20 movable into engagement with the surface of either roll when fresh for bringing the latter to a surface speed substantially equal 25 to that of the web in use.

31. A web roll changing mechanism comprising means for revolubly supporting a fresh roll and a roll in use, and driving means disposed between said rolls and movable 30 into engagement with the surface of either roll when fresh for bringing the latter to a surface speed substantially equal to that of the web in use.

32. A web roll changing mechanism comprising means for revolubly supporting in operative position for alternative use a fresh roll and a roll in use, driving means movable 35 into engagement with the surface of either roll when fresh for bringing the latter to a surface speed substantially equal to that of the web in use, and a rocking support for said driving means.

33. A web roll changing mechanism comprising means for revolubly supporting a fresh roll and a roll in use, driving means 45 disposed between said rolls and movable into engagement with the surface of either roll when fresh for bringing the latter to a surface speed substantially equal to that of the web in use, and a rocking support for 50 said driving means.

34. A web roll changing mechanism comprising means for revolubly supporting a fresh roll and a roll in use, and a traveling belt movable into engagement with the surface 55 of either roll when fresh for bringing the latter to a surface speed substantially equal to that of the web in use.

35. A web roll changing mechanism comprising means for revolubly supporting a 60 fresh roll and a roll in use, and a traveling belt disposed between said rolls and movable into engagement with the surface of either roll when fresh for bringing the latter to a surface speed substantially equal to 65 that of the web in use.

36. A web roll changing mechanism comprising means for revolubly supporting a fresh roll and a roll in use, a reversible endless belt movable into engagement with the 70 surface of either roll when fresh for bringing the latter to a surface speed substantially equal to that of the web in use, and means for driving said belt.

37. A web roll changing mechanism comprising means for revolubly supporting a fresh roll and a roll in use, a reversible endless belt disposed between said rolls and movable 75 into engagement with the surface of either roll when fresh for bringing the latter to a surface speed substantially equal to 80 that of the web in use, and means for driving said belt.

SAMUEL G. GOSS.
